UNITED STATES PATENT OFFICE.

LEON BUSHA, OF MINNEAPOLIS, MINNESOTA.

SHINGLE.

Application filed April 9, 1926 Serial No. 100,855.

This invention relates to strip shingles carrying a plurality of butts and preferably constructed from roofing felt or material of similar nature covered with a mineral coating of some finely divided hard substance, such as stone or slate.

It is an object of the invention to provide roofing material comprising two different strips or shingles cut out in pairs from a roll or sheet of material crosswise thereof which will, when laid, form a thatched roof having a series of undulating edges irregularly arranged.

A further object of the invention is to cut each of said two different shingles so that the longitudinal edges thereof will all be differently shaped, although the longitudinal edges on one shingle will be complementarily shaped with the respective longitudinal edges on the second shingle whereby the shingles may be cut out in pairs from a roll or sheet of material crosswise thereof without waste. By forming each longitudinal edge of the two designs of shingles differently, various irregular and tortuous lines may be formed in a roof laid with said shingles and either of the longitudinal edges of each shingle may be disposed downwardly as desired. In other words, both of the shingles or units are reversible edge for edge.

These and other objects of the invention will be apparent from the following description made in connection with the accompanying drawings wherein like characters refer to similar parts throughout the several views, and in which

Fig. 1 is a plan view of one of the pair of strips or shingles embodying the invention,

Fig. 2 is a similar view of the other strip or shingle embodying the invention.

Fig. 3 is a plan view of a portion of a sheet of material cut out to form the pairs of shingles or strips, and

Fig. 4 is a plan view of a plurality of each of said shingles arranged and laid to cover a roof and present a thatched appearance.

The shingles are preferably constructed from a foundation sheet of wool felt or other similar material with a coating of some self-hardening material, such as pitch or asphalt on one surface thereof and with a layer of finely divided hard material, such as slate or stone thrust through the coating and embedded therein.

In the drawings two different and distinct shingles are shown indicated by the letters A and B respectively, cut in pairs crosswise of a sheet or roll of material. Shingle A illustrated in Fig. 1 has its longitudinal sides 1 and 2 cut on different non-parallel tortuous lines. The ends 3 of shingle A are parallel to each other and perpendicular to the longitudinal center line of the shingle.

Shingle or section B (see Fig. 2) has its longitudinal edges cut on non-parallel tortuous lines 4 and 5, the edge 4 being complementarily formed with edge 2 of shingle A and the edge 5 of shingle B being complementarily formed with edge 1 of shingle A. Thus it will be seen that the combined width of shingles A and B will be equal through all points across the width of the roll from which said shingles are cut.

Fig. 3 illustrates the manner in which the shingles are cut crosswise from the roll or sheet. The dotted lines indicate the edges of the sheet and it will be obvious that there will be only a very small amount of waste in cutting the first shingle from the roll indicated by the cut out corner portions x and y respectively. A plurality, shown as three in the drawings, of slots 6 are cut intersecting the complementary edges of a pair of shingles and parallel with the ends of the sheet or roll. These slots, it will be seen, have their ends aligned at right angles to the longitudinal edges of the roll and they extend at various depths into the separate shingles, thereby forming four butts on each longitudinal edge of each shingle. In shingle A the butts on the upper longitudinal edge are numbered 7, 8, 9 and 10, while the butts on the lower longitudinal edge are numbered from left to right 11, 12, 13 and 14.

The butts formed on the upper longitudinal edge of shingle B are numbered 15, 16, 17 and 18 respectively and the butts on the lower edge are numbered 19, 20, 21 and 22 respectively. Notched recesses z are cut out from the outer edges of the ends of each shingle adapted to form slots similar in shape to the slots 6 when two shingles are abutted end for end as shown in Fig. 4. Notched recesses z also form nailing flanges 100 at the ends of the shingles.

It will be seen that each butt formed on the two shingles is differently shaped from every other butt on the two shingles and will simulate a great variety of separate shingles 110

or pieces of slate when the roof is laid. Every butt, however, has a complementary shaped butt on the other shingle of the pair.

In laying the shingles upon a roof, parallel 5 horizontally extending lines are usually drawn on the roof on which the nailing flanges at the ends of the shingles A and B may be gauged. The shingles A and B may be then laid on with the desired longitudinal 10 edge downward, the nailing flanges of one shingle abutting the nailing flanges of another shingle laid along the side thereof. The shingles are preferably broken on the third 15 when the succeeding layers are laid but may of course be broken on the half if desired. However, by breaking on the third it will be obvious that every part of the roof is covered with two layers of solid material there above in spite of the slots 6. The beauty of the 20 design obtained by laying the shingles is largely a matter of the skill of the roof layer in quickly picking the proper shingle A or B and turning the longitudinal edge downward to obtain the effect of a series of undulating 25 edges arranged in non-parallel relation and almost coinciding in some points while spaced farther apart at other points.

It is of course apparent that while curved 30 lines have been shown as forming the longitudinal edges of the separate shingles, the points of the several butts may be connected by straight lines to form irregular and tortuous longitudinal edges all within the scope 35 of this invention. Curved lines, however, give a slightly more pleasing appearance.

It is of course understood that I am not 40 limited to the use of four butts for each shingle or strip, but that a greater or less number may be employed as desired and that various curves or tortuously extending lines may be employed to cut the longitudinal edges of

the shingles. It will of course always be necessary, if the shingles are to be cut from a sheet or roll without waste, to have the edges 1 and 2 of shingle A complementary with the 45 edges 4 and 5 of shingle B.

It will be apparent that the amount of waste in the sheet or roll in cutting my shingles is extremely small, being only the small corner portions left in starting to cut the roll 50 and that left at the end of the roll and the amount cut out for the slots 6 and notched recesses α forming the several butts.

What is claimed is:

1. Roofing material for thatched roofs comprising 55 two shingle strips cut from a sheet of material forming a four-sided figure having two opposite straight and parallel sides, said strips being cut transversely so that they have their remote sides irregularly curved 60 and substantially parallel and the contiguous sides so cut that the sides of each strip adjacent one end are oppositely curved and said sides adjacent its other end are similarly curved and substantially parallel, the opposite curved sides of each sheet being non-symmetrical about any axis located therebetween.

2. Roofing material for thatched roofs including 70 two shingle strips cut from a sheet of material comprising a four-sided figure with two straight parallel sides, the other pair of opposite sides being curved and substantially parallel and the cut forming the contiguous sides being in the form of an irregular curve so that said contiguous sides are 75 complementary and the opposite curved sides of each strip are non-symmetrical about any axis located therebetween.

In testimony whereof I affix my signature.

LEON BUSH.
